Say Watson E. Coleman
Attorney

UNITED STATES PATENT OFFICE.

FLOYD V. ALBRIGHT, OF TERRA ALTA, WEST VIRGINIA.

GRAIN-MEASURER FOR THRESHING-MACHINE ELEVATORS.

1,325,602.

Specification of Letters Patent. Patented Dec. 23, 1919.

Application filed August 16, 1919. Serial No. 317,906.

To all whom it may concern:

Be it known that I, FLOYD V. ALBRIGHT, a citizen of the United States, residing at Terra Alta, in the county of Preston and State of West Virginia, have invented certain new and useful Improvements in Grain-Measurers for Threshing-Machine Elevators, of which the following is a specification, reference being had to the accompanying drawings.

This invention relates to an improved grain measurer for threshing machine elevators, and it has for its object to provide a device of this kind which, as the grain is elevated by the endless conveyer and then discharged into boxes or receptacles, may be manually manipulated so as to discharge the grain into bags, which are suspended upon the lower ends of the boxes.

20 A further object of the invention is to provide a grain measurer to control the grain in two receptacles or boxes, to permit the grain to be discharged from the boxes alternately and in requisite amounts in the bags.

25 A further object of the invention is to provide a pair of grain receiving boxes having swinging bottoms, and means for holding the bottoms in place, in combination with means for releasing the holding means alternately so that the grain in the boxes may be allowed to discharge alternately into bags.

30 A further object of the invention is the provision of means at the tops of the boxes actuated by the same means which releases the folding means for cutting off the flow of the grain into the boxes, or for deflecting the grain into one or the other of the boxes.

40 While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

45 The invention comprises further features and combination of parts, as will be herein-after set forth, shown in the drawings and claimed.

In the drawings:

Figure 1 is a view in side elevation of

my improved grain measurer as applied to threshing machine elevators;

Fig. 2 is a vertical sectional view;

Fig. 3 is a vertical sectional view on the line 3—3 of Fig. 2.

Referring to the drawings, 1 designates a casing in the bearings of which at the top and bottom are shafts 2 and 3, provided with the usual sprockets 4 and 5 and engaging the sprockets 4 and 5 is an elevator conveyer 6, adapted to elevate the grain from the lower part of the threshing-machine so that it may discharge through the opening 7. Forming a part of the casing 1 is an auxiliary casing 8 provided with a pair of grain receiving compartments or boxes 9 and 10. 70 A partition 11 divides the two receptacles and mounted in bearings of the auxiliary casing 8 is a shaft 12. A closure 13 is hinged at 14 to the upper part of the casing 1 and is positioned so as to close the upper part of the auxiliary casing 8, there being a suitable securing means 15 at the outer portion of the casing to hold the same in closed position.

80 Movable with the shaft 12 is a grain deflector 16, which may be moved to deflect the grain into the receptacle 9 or into the receptacle 10. The lower parts of the receptacles 9 and 10 terminate in contracted portions 17 and 18 which have hooks 19 to be engaged by the upper parts of the grain receiving bags 20, to receive the grain as it is discharged from the receptacles.

85 Pivoted at 21 are swinging closures 22, spring tensioned as shown at 23 in order to return the closures to their normal positions after permitting the grain to be discharged. Suitable abutments 24 are provided to be engaged by the closures 22 when they are returned to their normal positions. Mounted 95 in guides of the auxiliary casing is a slide 25. This slide is designed to engage under the closures to hold them in engagement with their abutments, so as to support the grain which enters the compartments.

100 Pivoted to the opposite sides of the auxiliary casing, as at 26, are rocking levers 27, the lower ends of which have sliding connections as at 28 with the slides 25, so that when the levers 27 are tilted in one direction or the other, the slide may be reciprocated so as to release one or the other of the closures 22. Also pivoted to the opposite

sides of the auxiliary casing as at 29 are additional rocking levers 30, which have slot and pin sliding connections 31 with the levers 27, so that as the levers 30 are tilted 5 the levers 27 will in turn be tilted.

Fixed to the opposite ends of the shaft 12 are arms 32 and 33 and the arm 32 terminates in an extension provided with a handle 34, that is, on one side of the auxiliary casing 8. Mounted in suitable guides 35 of the auxiliary casing is a scraper 36 which is in the form of a rectangular frame and is adapted to scrape the overflow of grain into the empty receptacle. The opposite ends of this scraper have pintles 37 which engage the slots 38 of the levers 30. The pintles 37 engage the slots 39 of the auxiliary casing, so that the scraper can be operated. When the arm 32 is grasped and 15 rocked, the deflector 16 may be moved in the direction of the arrow α , so that one of its edges will contact with the closure 13. When the arm 32 is so moved and the deflector, the slide 25 is moved in a direction 20 to release the closure of the receptacle 9 allowing the grain in the receptacle 9 to discharge into a bag which is suspended from the contracted lower end of the receptacle. When the slide 25 is moved to release the 25 closure 22 of the compartment 9, the slide 25 is moved under the closure 22 of the compartment 10 to support the same into raised position, allowing the grain to be supported thereon as it is discharged from the opening 30 35 7.

After the compartment 10 is sufficiently filled, say for instance substantially a bushel of grain, the deflector 16 may be returned to its normal position in which case the 40 grain will slide upon the upper part of the deflector into the compartment 9. In this case the grain will be supported upon the closure 22 of the compartment 9. As the deflector 16 and the closures 22 are alternately operated in this manner, the scraper is likewise operated, thereby scraping the 45 overflow of grain from the edges of the compartment.

Fastened on the side of the auxiliary casing 8 is a suitable grain register 8^a, for registering the amount of grain as it passes into the receptacles of the auxiliary casing 8. One side of the auxiliary casing 8 is provided with suitable sight openings 8^a and 55 8^b having glasses, whereby the operator may ascertain when the grain is high enough, so that the trip scraper can be operated, and also so that the trap doors or closures at the bottom of the receptacles may be opened, to 60 allow discharge of the grain. When the scraper is tripped, the surplus grain is scraped over into the empty receptacle or box.

The scraper 36 is provided at its opposite 65 ends with scraper parts 36^b which act to

scrape the surplus grain from the filled box or receptacle into the empty receptacle or box.

The invention having been set forth, what is claimed as new and useful is:—

1. In a grain measurer for grain elevators, the combination with a grain elevating means including a casing therefor, of an auxiliary casing having a pair of grain compartments to alternately receive the grain from the elevator, means for deflecting the grain into one or the other of said compartments, spring tensioned closures mounted in the lower portions of the compartments, means for holding the spring tensioned closures in raised positions, and a series of levers pivotally united and mounted on the opposite sides of the auxiliary casing for manipulating the deflecting means and the holding means alternately.

2. In a grain measurer for grain elevators, the combination with a dominant casing having a grain elevator therein, of an auxiliary casing having a pair of grain receiving compartments provided with a communication with the dominant casing, a deflector for deflecting the grain into one or the other of said compartments as it is elevated, spring tensioned closures mounted in the lower portions of the compartments to support the grain, abutments therefor, a member to hold the closures in contact with the abutments alternately, and means for actuating the deflector and the member to deflect the grain into one or the other of 100 said compartments and to alternately release the grain.

3. In a grain measurer for grain elevators, the combination with a dominant casing having a grain elevator therein, of an auxiliary casing having a pair of grain receiving compartments provided with a communication with the dominant casing, a deflector for deflecting the grain into one or the other of said compartments as it is elevated, spring tensioned closures mounted in the lower portions of the compartments to support the grain, abutments therefor, a member to hold the closures in contact with the abutments alternately, means for actuating the deflector and the member to deflect the grain into one or the other of said compartments and to alternately release the grain, said auxiliary casing having guides, a scraper mounted in said guides for removing the overflow of grain around the edges of the compartments, and link connections between the scraper and the operating means.

4. In a grain measurer for grain elevators, the combination with a dominant casing having grain elevating means mounted therein, of an auxiliary casing having a pair of grain compartments, swinging closures mounted in the lower ends of said compartments.

ments, abutments therefor, a member adapted to be moved alternately into the path of said closures to support them alternately in engagement with their respective abutments, 5 and means for actuating the member to alternately release said closures.

5. In a grain measurer for grain elevators, the combination with a dominant casing having grain elevating means mounted 10 therein, of an auxiliary casing having a pair of grain compartments, swinging closures mounted in the lower ends of said compartments, abutments therefor, a member adapted to be moved alternately into the path of 15 said closures to support them alternately in

engagement with their respective abutments, a rock shaft mounted in bearings in the outer part of the auxiliary casing and having a deflector to deflect the grain into one or the other of said compartments, a pair of 20 arms fixed to the opposite ends of said shaft, and toggle link connections having sliding connections with said member, certain of said toggle links having sliding connections with said arms whereby as one of said arms 25 is rocked the member is reciprocated alternately with the deflector and vice versa.

In testimony whereof I hereunto affix my signature.

FLOYD V. ALBRIGHT.
